PUMP CONSTRUCTION

William Horace Hazard, Dubuque, Iowa, assignor
to A. Y. McDonald Mfg. Co., Dubuque, Iowa,
a corporation of Iowa

Application October 30, 1939, Serial No. 301,874

1. Claim. (Cl. 103—221)

My invention relates to splash prevention and water drainage means for deep well pumps and has particular reference to means for preventing the splashing of water into the operating parts of the pump which may leak past the piston in a differential cylinder used in connection with deep well pumps, and draining the water from the operating parts of the pump.

Another and further object of my invention is the provision of means for catching and preventing water splashing out of a differential cylinder and into the power operating parts of a deep well pump and interfering with the operation of the parts, and also preventing the water from becoming mixed with the oil used for lubricating the various parts of the power operated mechanism, thereby adding long life to the operating parts and reducing to a minimum the care and expense necessary for operation of the pump.

Another and further object of my invention is the provision of means surrounding the differential cylinder of a deep well pump whereby water, due to leakage past the piston in the differential cylinder, is drained back into the well or away from the operating parts of the pump, thereby increasing their efficiency of operation and also making sure that the water does not collect in pools around the operating parts of the pump.

In pumps of this character it will be understood that usually the pumping cylinder is placed deep in the well, usually below the water level, and the water is lifted on the upstroke of the piston through a pipe into the pump and to a pressure tank. It has become common practice to provide differential cylinders to equalize the motor load and to cause the motor to operate more smoothly, thereby functioning better. The differential cylinder has a piston therein which operates on the downstroke and forces the water out of the discharge chamber into a pressure tank or out of the pump. The work stroke of the pump piston being on the upstroke and that of the differential cylinder on the downstroke equalizes the load on the motor and smoothes out the operation of the pump as a whole.

In my improved pump I provide a differential cylinder which is mounted in the discharge casing of the pump, which cylinder has a piston therein which functions to force the water out of the discharge casing on its downward stroke and into a storage tank against the water so the motor load is equalized. Above the piston I provide means to prevent the splashing of the water

past the piston head and means whereby leakage past the piston head is caught and ultimately drained away from the differential cylinder.

These and other objects of my invention will be more fully and better understood by reference to the accompanying sheets of drawings, and in which—

Figure 1 is a side view, partially in section and partially in elevation, of a completed pump embodying my invention;

Figure 2 is a top plan view of the differential cylinder and air pump and casing therefor, shown in Figure 1;

Figure 3 is a vertical sectional view showing the differential cylinder, air pump and discharge chamber used in connection with my deep well pump; and

Figure 4 is a view partially in section and partially in elevation, illustrating an end view of the apparatus shown in Figure 3.

Referring now specifically to the drawings, and in which like reference characters refer to like parts throughout, a housing 10 is shown having a base portion 11 adapted to be fastened upon any suitable foundation, such as concrete or the like, with a transverse wall 12 being provided in the bottom of the housing 10 to provide an oil sump in which oil is contained for lubrication of the various power operating parts of the mechanism. Side plates 13 and 14 are provided which are secured to the sides of the housing 10 in any approved manner, thus providing a substantially enclosed housing for the power operating parts of the pump.

Mounted upon the top of the housing 10 is a motor bracket 15 upon which motor rails 16, 16 are secured, to which the base 17 of an electric motor 18 is secured. A drive pulley 19 is mounted on the motor shaft over which a plurality of V-belts 20 pass and over a fly wheel 21, external of the housing 10 and outside of the pulley side plate 13. The fly wheel 21 is mounted upon a drive shaft 22 having a pinion 23 mounted on or formed integrally therewith and in engagement with a double crank gear 24 mounted upon a shaft 35 the ends of which are mounted in the side plates 13 and 14. Eccentrics 36 are formed integrally with the gears 24 on the outer faces thereof, with their axes of rotation upon the shaft 35 and upon which a pair of connecting rods 37, 37 are mounted which in turn are connected to a walking beam 38 at their upper ends by means of a wrist pin 39. The walking beam 38 at its rear end is mounted upon a fulcrum pin 40 to the outer ends of which an oscillating link

41 is mounted upon pins 42 at their lower ends, the outer ends of which pins 42 are, in turn, mounted in the side plates 13 and 14. A pair of compensating links 43, 43 are mounted at their outer ends upon pins 44, 44 fixed in the side plates 13 and 14 and at their inner ends upon the connecting rod wrist pin 39, all of which mechanism has to do with the application of power to the pumping means proper, more particularly hereinafter described.

Secured to one side of the housing 10 is a casing 45 which is supported upon a shoulder 46 formed upon the housing 10, and is secured by means of bolts 47 to the housing 10, and which forms a discharge chamber for the pump. The casing 45 has a pump pipe 48 connected thereto at its bottom and a discharge pipe 49 connected thereto at one of its sides which leads to a pressure tank or other suitable receptacle for receiving the water, and has a chamber 50 therein within which the water is received from the pump pipe 48. Mounted in the casing 45 is a gland sleeve 51 having a cup-shaped portion 52 at its upper end with an opening through the cup-shaped portion 42 to which a drain pipe 53 is preferably attached to convey water collecting in the cup-shaped portion 52 of the gland sleeve back into the well or to any other suitable desired place. The gland sleeve 51 is held in position on the casing 45 by means of bolts 54, 54 passing through trunnions 55, 55 on the gland sleeve 51, and through suitable cooperating trunnions 55, 56 formed on the casing 45. The casing 45 has a cup-shaped projection 57 at its upper end within which the upper end of the gland sleeve is received, with the space within this member being filled with packing 58 if desired, thereby cushioning and holding the gland sleeve in position in the casing 45.

Mounted within the gland sleeve 51 is a differential cylinder 60 having openings 61 in the side walls thereof opposite the cup-shaped portion 52 of the gland member. The cylinder 60 is in alignment with the water pipe 48 and has the pump rod 62 extending vertically therethrough, the lower end of which is threaded and to which additional sections of the pump rod 62 are secured for the purpose of operating the pump cylinder. The piston is mounted on the pump rod 62 in the cylinder 60. It comprises a follower 63 at the lower end thereof in threaded engagement with the rod 62, a spider 64 over which a cup leather 65 is placed, and a second spider 66 mounted thereabove with an additional cup leather 67 mounted over the spider 66. An upper follower 68 is provided having a trunnion portion 69 on the upper face thereof upon which a splash ring 70 is positioned having packing 71 between the upper and lower parts thereof. A lock nut 72 is provided which locks this assembly together with the space 73 provided between the lower side of the splash ring 70 and the piston follower 68, within which water, working past the pump leathers in the operation of the pump, may collect. The piston rod 62 is connected to a bracket 74 at its upper end, the bracket in turn being connected to the walking beam 38, one end of which extends through an opening 75 in the edge wall of the housing 10.

Mounted in the casing 45 is an air cylinder 76 within which an air piston 77 is mounted on a piston rod 78, the upper end of which is secured to an extension 79 of the bracket 74. A check valve 80 is provided at the lower end of the air

pump with a passage 81 below the check valve leading to a discharge chamber in the casing 45. A wall 82 is provided in the discharge chamber 45 with a check valve seat 83 therein and a check valve 84 mounted thereon. A spring 85 is provided which normally keeps the check valve 84 in position upon the seat 83. A cap 86 is provided having an opening 87 therein through which the pump rod 62 passes, with a screw 88 passing through the cap 86 so that it is held in position over the upper end of the differential cylinder 60. The cap 86 has downwardly turned flange portions directed toward the cup-shaped portion 52 on the gland sleeve 51, with channels 89, 89 therein into which water passing the splash ring and directed upward by the action of the piston in the differential cylinder may be received and directed downward into the cup-shaped receptacle, where it is drained away from the differential cylinder and back to the well or some other suitable discharge source.

From the foregoing description it is believed that the operation of the device will be very easily and quickly understood in that during the pumping operation water is lifted into the chamber 50 by the pump cylinder on the upstroke of the piston, this water filling the chamber 50 and also the differential cylinder 60. On the downstroke of the piston the water being held in the well cylinder by a suitable check valve, is forced out of the discharge chamber 50, past the check valve 84 and into the discharge pipe 49, usually leading to a pressure tank or the like. With the same stroke the air is forced out of the air cylinder 86 and out through the discharge pipe 49, thereby maintaining a suitable pressure on the pressure tank.

In operation of the device water will necessarily leak past the leathers 65 and 67 and normally should be trapped in the space 73 above the piston follower 68 and splash rings 70. On the upstroke of the piston, the splash ring 70 passes above the opening 61 so that this water drains out into the cup-shaped portion 52 and is carried away through the opening in the side wall and drainage pipe 53. If the water passes the splash ring 70 into the upper portion of the cylinder and fails to drain out through the opening 61 as the piston passes upward, this water is forced against the cap 86 into the channels 89 where it is directed downward into the cup-shaped portion 52 of the gland member 51 where it is drained away from the pump and is prevented from splashing upward and out of the top of the differential cylinder and through the opening 75 in the housing 10, where it may become mixed with the lubricating oil and with the power operating parts of the pump. In this manner all water which passes the piston in the differential cylinder is drained away from this cylinder and also is prevented from splashing about in the pump housing. A casing 90 is removably secured upon the casing 45 and against the housing 10 and supported by the discharge casing 45 to protect the differential cylinder and air pump during operation.

While I have described more or less precisely the details of construction, I do not wish to be understood as limiting myself thereto, as I contemplate changes in form and the proportion of parts and the substitution of equivalents as circumstances may suggest or render expedient without departing from the spirit or scope of my invention.

I claim:

In combination with a deep well pump, a casing having a water discharge chamber therein, a differential cylinder mounted in said casing having a drain opening in the wall thereof, a piston in said cylinder, a removable splash ring spaced apart from the piston head in engagement with the walls of the cylinder and to move

with the piston head whereby a water receiving chamber is formed above the piston head, the water receiving chamber above the piston head coming into register with the opening in the cylinder wall only at the top of the upstroke of the piston.

WILLIAM HORACE HAZARD.
